[57] CLAIM

The ornamental design for a tire for a vehicle wheel, as shown and described.

DESCRIPTION

FIG. 1 is a perspective view of a tire for a vehicle wheel showing my new design it being understood that the tread pattern is repeated throughout the circumference of the tire as shown schematically by solid line, the opposite side being the same as that shown;

FIG. 2 is a front elevational view thereof; and

FIG. 3 is a side elevational view thereof on a reduced scale, the opposite side being a mirror image of that shown.

FIG 1

FIG 2

FIG 3
